UNITED STATES PATENT OFFICE.

FLORENCE M. McCARTHY, OF ST. LOUIS, MISSOURI, ASSIGNOR OF ONE-HALF TO JAMES W. BYRNES, OF ST. LOUIS, MISSOURI.

LEATHER-WORKING MACHINE.

1,354,572.

Specification of Letters Patent.

Patented Oct. 5, 1920.

Application filed October 4, 1919. Serial No. 328,414.

To all whom it may concern:

Be it known that I, FLORENCE M. McCARTHY, a citizen of the United States, residing at St. Louis, Missouri, have invented 5 a certain new and useful Improvement in Leather-Working Machines, of which the following is a full, clear, and exact description, such as will enable others skilled in the art to which it appertains to make and 10 use the same.

This invention relates to leather working machines, and particularly to machines of the kind that are used for cutting the end portions of strips of leather which are to 15 be lapped and connected together.

In the manufacture of leather driving belts it is the usual practice to skive off the end portions of the strips of leather from which a belt is to be formed by means of a 20 machine generally termed a scarfing machine, then bevel off the extreme ends of the strips in a tipping machine so as to form feather edges at the ends of the strips, and thereafter, scrape the skived end portions of 25 the strips with a hand scraper so as to remove the ridges that are produced by tipping or feather edging the strips. This hand scraping operation is slow and requires considerable skill and care on the part of 30 the operator in order to produce a true and even surface and to avoid tearing the feather edged ends of the strips, and even with skilful operators, the feather edged end of the strips are frequently torn.

35 The main object of my invention is to provide a means for mechanically removing the ridge on a strip whose end portion has been skived and then feather edged without liability of tearing the feather edged end 40 of the strip.

Another object is to provide an efficient machine of simple construction for finishing the end portions of strips of leather which are to be connected together by lapped 45 joints, said machine being so constructed that it can be adjusted easily to adapt it to strips having scarfed or skived end portions of varying lengths.

Figure 1 of the drawings is a top plan 50 view of a leather working machine constructed in accordance with my invention.

Fig. 2 is a front elevational view of said machine.

Fig. 3 is a side elevational view of a portion of the machine. 55

Fig. 4 is also a side elevational view, illustrating the work support in the position it occupies at the end of the cutting operation.

Fig. 5 is a side elevational view of a strip of leather whose end portion has been skived 60 off in a scarfing machine.

Fig. 6 is a side elevational view of said strip after the extreme end of same has been finished or feather edged in a tipping machine; and 65

Fig. 7 illustrates said strip after the end portion of same has been finished in my improved machine.

Referring to Figs. 1 to 4 of the drawings, which illustrate the preferred form of my 70 invention, A designates a rotatable cutter that revolves in the direction indicated by the arrow ω in Fig. 3, and B designates a work support which is so constructed that when a leather strip S of the kind shown in 75 Fig. 5 is arranged in operative position on said work support and fed to the cutter A, said cutter will remove the ridge s on the skived or scarfed portion f of said strip, and thus produce an even surface s^2 that inclines 80 upwardly gradually from the feather edged end s^3 of the strip. Various types or kinds of cutters can be used and any preferred method can be used for mounting the cutter and driving same. In the machine herein 85 illustrated the cutter A consists of a cylinder secured to a horizontally-disposed shaft 1 and provided on its periphery with angularly-disposed cutting blades or knives 2, said shaft 1 being rotatably mounted in a 90 stationary supporting structure 3, and provided with a pulley 4 over which a driving belt 5 passes. The work support B can also 95 be formed in various ways without departing from the spirit of my invention, but when the machine is provided with a rotatable or revoluble cutter, it is preferable to construct the work support B so that it can be rocked or oscillated and provide said work support with an eccentrically-disposed 100 surface on which the underside s^4 of the end portion of the strip bears when the lap or scarfed end portion of said strip is being leveled or evened up. Accordingly, I have 105 illustrated the work support B as consisting of a cylindrical shaped member arranged

horizontally in front of the cutter A and provided with an eccentrically-disposed surface 6 on which the under side of the skived or scarfed end portion of the strip is supported during the cutting operation.

- 5 The work support B is normally spaced away from the cutter A and means is provided for moving said elements toward and away from each other so as to bring 10 the work on the work support into operative position to be engaged by the blades or knives of the cutter. One convenient way of accomplishing this is to mount the work support B on a movable frame 7 that is 15 adapted to be actuated by a foot treadle 8 or other suitable device under control of the operator in charge of the machine. The work support carrying frame 7 of the machine herein illustrated is pivotally connected at 9 to brackets on the stationary frame-work 3 of the machine and is connected to the foot treadle in such a manner that when said treadle is depressed the work support B will move rearwardly toward the 20 cutter A. When the treadle 8 is released the work support B is moved forwardly away from the cutter by means of a spring 10 connected to the stationary frame 3 of the machine and to the movable work support carrying frame 7 at a point below the 25 axis about which said frame 7 swings. Any preferred means may be employed for limiting the movement of the work support B toward the cutter A, the means herein 30 illustrated for this purpose consisting of adjustable stops 11 on the stationary frame 3 of the machine that engage and limit the movement of the swinging frame 7 when said frame is depressed by the foot treadle 8. 35 40 The work support B is mounted in the frame 7 in such a manner that it can be rocked or oscillated about a horizontal axis parallel to the longitudinal axis of the cutter A, and means is provided for normally 45 holding said work support in such a position that the high point 60 of the eccentrically-disposed surface 6 thereon is arranged below the transverse center of the cutter A, as shown in Fig. 3. In the machine herein illustrated a torsion spring 12 (shown in Fig. 1) is provided for turning the work support B in the direction indicated by the arrow z in Fig. 3, so as to hold 50 a stop 13 on said work support in engagement with a stationary stop 14 on the frame 7 in which the work support is mounted. During the cutting operation the work support B is revolved in the opposite direction, 55 namely, forwarded away from the cutter A, as indicated by the arrow z in Fig. 4, and in order to limit the forward movement of the work support, the frame 7 is provided with a second stop 14^a against which the stop 13 on the work support strikes. I wish 60 it to be understood, however, that it is im-

material, so far as my invention is concerned, what means is employed for limiting the oscillating movement of the work support and for holding said work support in its normal position.

70 In using the machine the operator inserts the scarfed or skived end portion of a strip of the character shown in Fig. 6 between the cutter A and the eccentrically-disposed surface 6 on the work support B, being careful to see that the extreme end of the strip is in alinement, or approximate alinement, with the high point 60 on the eccentrically-disposed surface 6. The operator then depresses the foot treadle 8 so as to move the 75 work support B rearwardly toward the cutter A, thus causing the strip to be so positioned with relation to the cutter that the transverse center of the cutter is a trifle above the inner end of the scarfed or skived 80 portion of the strip. Thereafter, the operator pulls the strip upwardly so as to revolve the work support B forwardly or in the direction indicated by the arrow z in Fig. 4, due to the frictional engagement 85 between said strip and work support, and thus cause the cutter to remove sufficient leather from the top side of the scarfed end portion of the strip to form a uniform and even surface which inclines upwardly 90 gradually from the feather edged end of the strip, as shown in Fig. 7, the work support being so designed and adjusted that the cutter shaves off a thin portion from the strip 95 beginning at the inner end of the scarf or 100 lap and terminating adjacent the feather edged end of the strip.

In order that the machine may be used for 105 finishing strips having skived or scarfed end portions of varying lengths, the work support B is provided with a plurality of eccentrically-disposed surfaces 6^a of varying lengths, and the stop 13 on said work support is so mounted that it can be arranged in various positions to coöperate with the 110 stationary stops 14 and 14^a when one or the other of the eccentrically-disposed surfaces 6^a is being used to support the strip being finished. In the machine herein illustrated the work support B merely consists of a 115 cylindrical-shaped member provided at its ends with trunnions 15 that turn in bearings in the frame 7, and the eccentrically-disposed surfaces on said work support are formed by rectangularly-shaped pieces of 120 leather or other suitable material of substantially wedge shape in transverse cross section.

125 While I have herein described my invention embodied in a machine for finishing strips having skived or scarfed end portions that are slightly irregular or uneven, I wish it to be understood that my invention is not limited to a machine that is used for the particular purpose mentioned.

Having thus described my invention, what I claim as new and desire to secure by Letters Patent, is:

1. A leather working machine, comprising a revolving cutter, an oscillating work support arranged to rock about an axis extending parallel to said cutter for moving the work relatively to the cutter during the cutting operation, and an eccentrically-disposed surface on said work support for supporting the work on which the cutter operates.

2. A leather working machine, comprising a revolving cutter, and a rockable or oscillating work support arranged in proximity to said cutter and provided with an eccentrically-disposed surface for supporting the work, said work support being adapted to be rocked during the cutting operation in such a direction that the high point of the eccentrically-disposed surface thereon will move toward the cutting zone of said cutter.

3. A leather working machine, comprising a horizontally-disposed, rotatable cutter, a rockable work support arranged at one side of said cutter in parallel relation to same, an eccentrically-disposed surface on said work support for supporting the work being operated on, and means for enabling said cutter and work support to be moved toward and from each other, the work support being adapted to be revolved to feed the work to the cutter.

4. A machine for finishing a strip having a feather edged end and a scarfed portion that terminates in a ridge, comprising a revolving cutter, and means for supporting the strip and moving it relatively to the cutter, in a direction opposite to the direction of movement of the cutter and in such a manner that the cutter will remove said ridge and form a regular, even surface on the strip that inclines upwardly from the feather edged end of the strip.

5. A machine for finishing a strip having a feather edged end portion and a scarfed portion that terminates in a ridge, comprising a revolving cutter, an oscillating work support arranged in proximity to said cutter and adapted to be rocked in a direction opposite to the direction of rotation of the cutter to present the strip to the cutter, and an eccentrically-disposed surface on said work support on which the underside of the end portion of the strip bears.

6. A machine for finishing a strip having a feather edged end portion and a scarfed portion that terminates in a ridge, comprising a cutter, an oscillating work support ar-

ranged in proximity to said cutter, and an eccentrically-disposed surface on said work support on which the underside of a portion of the strip bears, said work support being adapted to be rocked in a direction to move the strip past the cutting edge of the cutter and cause the high point of the eccentrically-disposed surface on said work support to be carried inwardly toward the cutting edge of the cutter, thereby causing the cutter to remove a thin shaving from the top side of the strip.

7. A leather working machine, comprising a rotatable cutter, an oscillating work support arranged in proximity to said cutter, and a plurality of eccentrically-disposed surfaces of different lengths on said work support for supporting the work to be operated on.

8. A leather working machine, comprising a rotatable cutter, an oscillating work support arranged in proximity to said cutter provided with an eccentrically-disposed surface on which the work is supported, a movable frame on which said work support is mounted, and means for actuating said frame so as to move the work into operative position with relation to the cutter.

9. A leather working machine, comprising a rotatable cutter, a work support arranged in proximity to said cutter and consisting of a cylindrical-shaped member provided with an eccentrically-disposed portion on which the work is supported, a movable frame in which said work support is journaled, and means that exerts pressure on said work support in such a manner that the eccentrically-disposed surface thereon normally occupies a certain position with relation to the cutting zone of said cutter.

10. A leather working machine, comprising a rotatable cutter, a pivotally mounted frame arranged in front of said cutter, a cylindrical member journaled in said frame and provided with a work supporting surface that is eccentrically-disposed with relation to the axis of said member, means under control of the operator for moving said frame so as to bring the work supporting member thereon into close proximity to the cutter, a spring for moving said frame in the opposite direction, means for limiting the swinging movement of said frame, a stop on said work supporting member that cooperates with a stop on said swinging frame to limit the movement of said work supporting member relatively to said frame, and means for normally holding said stops in engagement with each other.

FLORENCE M. McCARTHY.
